GAS AND AIR MIXING DEVICE

Walter E. Benjamin, Anderson, Ind., assignor to
 The Pierce Governor Co., Anderson, Ind., a
 corporation

Application October 29, 1934, Serial No. 750,439

6 Claims. (Cl. 137—111)

This invention is directed to a gas and air mixing device to secure perfect operation of an internal combustion engine when using either artificial gas, natural gas, a blend of artificial and natural gas, gases derived from hydro-carbons and compressed to a liquid state and maintained in that state until released for combustion purposes, or any fuel that may be reduced to a gaseous form, then introduced to the engine or 10 mixed with air in their proper proportions for use in operating an internal combustion engine.

The chief object of this invention is to provide a device which will maintain a uniform 15 gas-to-air ratio throughout the entire range of engine operation.

Another and auxiliary object is to provide a device which is capable of ready adjustment to the B. t. u. content of the fuel gas used for combustion and the regulation is determinable 20 by the heat unit analysis of the fuel in its gaseous form.

Another object of the invention is to introduce at substantially atmospheric pressure the fuel 25 in its gaseous form to the air stream for mixing, so that for at all throttle positions and for different types of fuel gas (having reference to the B. t. u. content) the air and fuel gas are mixed at substantially atmospheric pressure, 30 thereby eliminating variations that heretofore have been inherent in present commercial jet or velocity gas and air mixing devices, since, if the gaseous fuel is introduced to the air stream under a pressure other than atmosphere for a 35 certain type of engine operation, such as normal speed, the variation in the throttle position will usually result in a different variation in the air-to-fuel gas ratio.

The chief feature of the invention consists in 40 constructing the device whereby all of the aforesaid objects may be accomplished.

The full nature of the invention will be understood from the accompanying drawing and the following description and claims:—

45 In the drawing Fig. 1 is a central sectional view through the fuel and air intake passages to the gas and air mixing device, the mixing chamber, the valving chamber and the valve portion itself, the latter being shown in elevation.

50 Fig. 2 is a sectional view taken on line 2—2 of Fig. 1 and in the direction of the arrows.

Fig. 3 is a similar sectional view taken on line

3—3 of Fig. 1 and in the direction of the arrows.

55 Fig. 4 is a perspective view of the valve mem-

ber, the actuating member associated therewith and the fuel-to-air ratio adjusting member.

Fig. 5 is a top plan view of the device.

In the drawing, 10 indicates an air intake passage and positioned adjacent thereto is a gaseous 5 fuel intake passage 11. Herein the walls forming the passages are shown united and may be suitably secured to the valve body portion 12. The passage 10 communicates with a rectangular passage 13 in the valve body 12 as at 14, 10 and the port extends entirely across and through the same. The passage 11 communicates with a parallel rectangular passage 15 by means of the port 16. Passage 15 extends entirely through 15 the valve body 12.

The opposite ends of the two passages 13 and 15 discharge at substantially the same level into a mixing chamber 17, the mixing chamber being herein shown detachably secured as at 18 to the valve body. The mixing chamber includes the 20 apertured threaded portions 19 for detachable anchorage to the intake of the internal combustion engine which is not shown therein.

Extending entirely through the body 12 is a 25 cylindrical chamber 20. This chamber 20 is closed at one end as at 21 by any suitable means, such as that illustrated. Its opposite end is enlarged and threaded as at 22. A cylindrical valve member is both rotatably and slidably mounted in said cylindrical valve chamber 20. The cylindrical valve member includes an end portion 23, an intermediate vane connecting portion 24, a cylindrical portion 25, a second vane or connecting portion 26 in longitudinal alignment with the first mentioned vane portion 24, and another cylindrical portion 27. The stem 28 rigidly therewith rotatably supports the externally threaded retainer 29 and an actuating arm 30 is suitably secured to the valve stem 28 as at 31.

The width of the vane 24 or distance between 35 the two adjacent faces of the portions 23 and 25, is equal to that of the width of the passage 13. The thickness of the portion 25 is equal to the width of the passage 15, plus the width of the wall portion 32 between the two passages 13 and 15. The distance between the two cylindrical 40 portions 25 and 27 is at least equal to the width of the passage 15 and preferably is equal to the width of the portion 25.

As shown in Fig. 1, the valve member has been 45 moved so that the cylindrical portions are displaced toward the left an amount such that the cylindrical portion 25 exposes or uncovers but half of the passage 15. Simultaneously with such exposure, the amount of restriction applied to the 50

passage 13 by the portion 25 is equal to the amount of effective opening of the passage 15. In other words, there is discharged into the mixing chamber 17 an amount of air and gaseous fuel 5 equal to the total volume that could normally pass unrestricted through the passage 13.

The axial position of the valve member is adjusted manually, determinable by the B. t. u. content of the gaseous fuel, so that the most effective 10 combustible mixture between the gaseous fuel and air is obtained. This is adjusted for full open throttle position. Should the B. t. u. content of the fuel be changed, the axial position of the cylindrical valve member would be changed to 15 obtain the most effective combustible mixture, that is, gas-to-air ratio at full open throttle position.

The parts are so proportioned that if the valve member were actually moved to the right until 20 only the vane 24 constituted the entire obstruction in the passage 13, then at that time there would be no gaseous fuel passage through the valve body that would be effective. Of course, the maximum effective air-to-gas ratio possible 25 in the opposite direction would be for the portion 25 to have its right hand edge substantially coincident with the right hand wall of passage 13 shown in Fig. 1, in which position, the cylindrical portion 25 would substantially block out half of 30 the total air passage.

In Fig. 5 the valve control is further illustrated. In this figure, the retaining member 29 is shown provided with a serrated edge 34 and suitably supported at 35 is a yielding latch 36 which engages 35 said edge and serves to retain the valve retainer and axial adjuster 29 in the adjusted position. Inasmuch as member 29 is confined between the hub portion of the lever 30 and the cylindrical portion 27 and is freely rotatable on 40 the stem 28, threading and unthreading movement of member 29 in the valve body serves only to shift the latter axially to the left or right, respectively. Said valve member movement does not disturb at all the throttle position of the 45 valve.

By this means the air-to-gas ratio may be changed at will without disturbing any of the connected throttle control mechanism. It will be noted that the total volume of air and gaseous 50 fuel entering the mixing chamber for any given throttle position is always constant, although the fuel and gas ratio may be different, depending upon the position of member 29. In other words, there is supplied to the mixing chamber 17 and 55 by it to the engine intake, a uniform volume of gaseous fuel and air for any given throttle position. The richness or leanness of the mixture can thus be regulated and will remain constant for all throttle positions with any given axial 60 setting of the valve.

The valve for throttle purposes is rotatable and herein such rotation is confined to oscillation. The lever 30 includes an extension 40 terminating in an abutment 41 adapted to engage 65 at the extremes of the oscillatory movement, the adjustably mounted stops 42 suitably supported by the valve body as by means of the plate 43 and the anchoring screws 44. Any other equivalent stop structure may be substituted without departing from the broad feature of the invention.

The mixing chamber 17 discharges to the intake of the internal combustion engine. It will 70 be apparent, therefore, that any control mech- 75

anism connected to the end 45 of the lever arm 30 will control the engine.

As is well known in the automotive engine field, a governor construction may be interposed between a manually operable throttle actuating member and the lever arm 30, so that this device is readily capable of incorporation in a fuel control system which is automatically controlled to regulate maximum speed by a governor operable by the engine itself or which will also permit the manual control of the engine by moving the valve member rotarily into the adjusted throttling position. In other words, the position of the arm 30 determines the amount of fuel gas of a uniform gas-to-air ratio that is supplied to 15 the intake of the engine. One stop limits the valve movement toward the closing or cut off position, which is close to 90° or 90° to that shown in Figs. 2 and 3, and this corresponds to the idling position of the engine. This is the 20 minimum amount of fuel gas necessary to have the engine operate and just turn over. The other stop is provided to limit the engine to the full throttle position. To have the engine operate at top speed, it may not be necessary to have the 25 valve member positioned as shown in Figs. 2 and 3, but the two vane portions may be at an angle to that shown. This other stop, therefore, is to prevent, in that event, the valve from being moved into the position shown in Figs. 2 and 3, 30 because such a position of the valve would supply more fuel gas than was necessary for the engine to operate at top speed.

It will be apparent, therefore, from the foregoing description that this gas and air mixing 35 device inherently is arranged to supply a predetermined amount of fuel mixture for any given throttle position of the valve and it is also capable of adjustment, independent of throttle positioning for varying the air to fuel gas ratio of the 40 volume, as required by the B. t. u. content of the fuel gas used.

It will also be evident that the fuel gas and the air are introduced into the chamber 17 at the same level and thus any suction of the engine 45 or any velocity of the air through the passage 10 and the passage 13 will have little or no effect on the amount of fuel gas supplied to the mixing chamber 17. Hence, there is no jet action incorporated in the device nor present therein, so 50 that the flow of fuel gas is always that determined by the two positions of the valve, that is the axial and the rotary positions. It is not in any way dependent upon the velocity of the air forming a part of the subsequent mixture. This 55 type of structure, therefore, permits the fuel gas to be supplied to the gas and air mixing device at substantially atmospheric pressure.

The device, as illustrated, represents the simplest form of the invention capable of supplying 60 to the engine, fuel gas of a uniform amount for any given throttle position and for different throttle positions supplying fuel gas having the predetermined fuel-to-air ratio selectively determined and for which the valve is adjusted.

The present invention is extremely simple since it includes but one movable unit for volumetric and fuel-to-air ratio control, said unit in turn including but three parts, the single valve member, the threaded member and the operating arm.

The present invention requires no additional special equipment such as an idling jet or the like, to accommodate all ranges of fuel gas or engine speeds. Also, since no Venturi or jet action is necessary for normal operation of the device,

the engine obtains the full benefit of its total manifold capacity, it, of course, being understood that the proper size device is applied to the engine; for example, in engine practice, the 5 intake manifold opening and inlet valve area is fixed by the engine manufacturer as determined by said manufacturer to be most efficient for the power and speed the engine is to have.

The present device is so arranged that if a 10 square inch of manifold intake is used in the engine, the size of the device is the same. Therefore, full freedom of flow of the maximum combustible mixture to the intake is possible.

Furthermore, if desired, an automatic fuel gas 15 cut-off device may be positioned ahead of the gas inlet to automatically stop the flow of fuel gas if the engine inadvertently should stop.

The device can be used in any position, that is, 20 for horizontal, down draft, or up draft carburetion.

The invention claimed is:—

1. A fuel gas-to-air ratio and throttle type control and mixing device, including a body having a cylindrical bore therein, with a pair of passages 25 having axes lying in a common plane communicating at their inner ends with the bore and a pair of larger passages having axes lying in a common plane communicating with the bore at their inner ends, the vertex of the angle formed 30 by the intersection of the axes of each pair of passages lying in the bore axis, the outer end of one passage of a pair of said passages being adapted for independent communication with a fuel supply and the outer end of one passage of 35 the other pair of said passages being adapted for independent communication with the atmosphere, the outer ends of the other two passages having common communication, a cylindrical valve member in said bore and of an axial length 40 less than the length of the bore, for axial and rotatable movement therein, closures for opposite ends of the bore, a stem rigid with the valve and rotatable and axially movable in one of the closures, and means carried by the stem for rotating 45 the valve, one of said closures having an adjustable connection with the body for axial ad-

justment of the valve therein, said cylindrical valve member including a recess in the periphery and of a width at least equal to the corresponding width of a passage of the pair of smallest passages and of an arcuate length sufficient to 5 simultaneously register with the bore communicating ends of said last mentioned pair of passages, said valve member including another recess in its periphery and offset axially from the first recess and of a linear width at least equal 10 to the corresponding linear width of a passage of the other pair of passages and of an arcuate length sufficient to simultaneously register with the bore communicating ends of said last mentioned pair of passages, said recesses being axially 15 separated an amount at least equal to the distance between the pairs of passages.

2. A device as defined by claim 1, characterized by the duplication of recesses symmetrically arranged with respect to the axis of the valve 20 member, the valve member including a portion between each pair of duplicated recesses constituting a control vane for the respective pair of 25 said passages.

3. A device as defined by claim 1, characterized by each pair of passages being coaxial.

4. A device as defined by claim 1, characterized by each pair of passages being coaxial, both 30 last mentioned coaxial alignments being coplanar.

5. A device as defined by claim 1, characterized by the duplication of recesses symmetrically arranged with respect to the axis of the valve member, the valve member including a portion 35 between each pair of duplicated recesses constituting a control vane for the respective pair of said passages, each pair of passages being coaxial.

6. A device as defined by claim 1, characterized by the duplication of recesses symmetrically arranged with respect to the axis of the valve 40 member, the valve member including a portion between each pair of duplicated recesses constituting a control vane for the respective pair of said passages, each pair of passages being coaxial, 45 both last mentioned alignments being coplanar.
